UNITED STATES PATENT OFFICE

136,293

DESIGN FOR A CASING FOR A CARPET SWEEPER OR SIMILAR ARTICLE

Ira June Owen, Laguna Beach, Calif., assignor of one-third to Julius H. Kiel and one-third to Robert B. Kiel, both of Wilmette, Ill.

Application April 21, 1942, Serial No. 106,956

Term of patent 14 years

To all whom it may concern:

Be it known that I, Ira June Owen, a citizen of the United States, residing at Laguna Beach, in the county of Orange and State of California,
have invented a new, original, and ornamental Design for a Casing for a Carpet Sweeper or Similar Article, of which the following is a specification, reference being had to the accompanying drawing, forming a part thereof.

In the drawing:

Figure 1 is a top plan view of the casing for a carpet sweeper or similar article, showing my new design;

Figure 2 is a rear elevational view of the casing; and

Figure 3 is a side elevational view of the same.
I claim:

The ornamental design for a casing for a carpet sweeper or similar article, as shown.

IRAJ. OWEN.
